UNITED STATES PATENT OFFICE.

SAMUEL DEACON, OF LYNN, MASSACHUSETTS, AND MERLE J. WIGHTMAN, OF HARTFORD, CONNECTICUT, ASSIGNORS TO THE THOMSON-HOUSTON ELECTRIC COMPANY, OF CONNECTICUT.

SOCKET FOR INCANDESCENT LAMPS.

SPECIFICATION forming part of Letters Patent No. 451,656, dated May 5, 1891.

Application filed March 15, 1890. Serial No. 344,041. (No model.)

*To all whom it may concern:

Be it known that we, SAMUEL DEACON, of Lynn, county of Essex, State of Massachusetts, and MERLE J. WIGHTMAN, of Hartford, 5 county of Hartford, State of Connecticut, have invented certain new and useful Improvements in Sockets for Incandescent Lamps, of which the following is a specification.

Our invention relates to certain details of 10 construction of the circuit-breaking switch in the lamp-circuit, which will be hereinafter set forth.

Referring to the accompanying drawings, 15 Figure 1 is a vertical section on line 1 1 of Fig. 6. Fig. 2 is a section on the line 2 2, Fig. 6. Fig. 3 is a section on the line 3 3, Fig. 6. Fig. 4 is an end elevation with the circuit open. Fig. 5 is a plan of the disk J. Fig. 6 is a plan 20 of the socket with the lamp removed, and it is taken from underneath relatively to the previous figures. Fig. 7 shows the switch when being operated, and Fig. 8 is a modification.

Referring to the drawings more particularly, A is an incandescent lamp having the two 25 wires connected to the carbon filament terminating, respectively, in the ring B and the central socket C. The central socket C is screw-threaded internally and adapted to receive a screw attached to the socket, by means 30 of which the lamp is held in place.

J is a disk of insulating material set in the holder D. On the under side of disk J are attached two U-shaped pieces of metal F and H, the latter being inverted and the two being 35 insulated from each other by the material of the disk. The lower transverse part of piece F is attached to the screw L, adapted to enter socket C. The piece F forms a supporting frame-work connecting the disk J and the 40 lamp, the latter being also surrounded by the usual casing. The piece H has its two legs perforated to form a bearing for the insulating-spindle K, which is turned by the handle E. The spring M is attached to the under side 45 of the horizontal part of the piece H and extends parallel therewith. On the end of spindle K is loosely pivoted a rectangular block G, which in its normal upright position is maintained between the spring M and the ring B,

forming an electrical connection between the 50 two, and thereby closing the circuit to the lamp. The block G is adapted to turn with the spindle K, but has considerable slack motion, so that the spindle K must be turned a certain distance by means of the handle E before it 55 engages with the block G, and the two move together. This gives to the switch a positive snap action, the circuit being broken suddenly and completely, so as to prevent arcing. Various devices may be employed to obtain this 60 loose action between the spindle K and the block G. In Fig. 1 I have shown a pin passing diametrically through spindle K and engaging with a slot in block G. In this case spindle K has the pin near its outer end, and 65 the part of the spindle projecting beyond the pin passes first through the block G, then through the slotted hole in the piece H, the latter feature being provided to allow a slight vertical play of the spindle, so that the block 70 G can always adjust itself between the spring M and the ring B. In Fig. 8 the pin is passed through the spindle at a point inside of the block G. In action the spindle K is first turned a short distance, when it engages with the 75 block G and tends to move it and turn the block with it. The block thus assumes the position shown in Fig. 7, where the spring M is raised to a distance from the ring B equal to the diagonal line of the rectangular block G, 80 and further movement throws the block G into a horizontal position with a snap movement, which completely severs the connection between spring M and the ring B, as shown in Fig. 4. 85

The circuit-connections are as follows: The two U-shaped pieces H and F, which are insulated from each other by the material of the disk J, are connected, respectively, to the two terminals of the wires leading from the supply-conductors into the socket, as shown in Figs. 1 and 3. These wires are indicated in all the figures except Fig. 7, and are marked X and Y. The former passes to the screw O, Figs. 2 and 3, on one side of the piece F, and the latter is connected to the screw R in a transverse extension from the piece H, Fig. 3. When, therefore, the switch is closed, the 90 95

circuit will be from wire X to the U-shaped piece F, to the screw L and socket C, thence through the filament of the lamp and back to the ring B, and from the ring B it is connected by the block G to the spring M, to the piece R, and thence to the wire Y.

My invention, while consisting in details, discloses a form of lamp socket and switch which is exceedingly cheap in construction and effective in action and separates the different parts of the circuit as far apart as possible in the necessarily limited space. It will also be seen that one of the lamp-terminals—namely, the central socket C—is adapted to connect directly with the insulated piece F, while the other insulated piece H is provided with a switch which bears directly upon the opposite lamp-terminal B. It has been heretofore customary to provide a third piece adapted to connect with one lamp-terminal and receive the switch-contact. Our invention dispenses with this third piece and its essential insulation and permits the switch to bear directly upon the terminal in the base of the lamp.

25 What we claim as new, and desire to secure by Letters Patent, is—

1. A lamp-socket switch consisting of a rectangular block, a spindle for turning the same loosely connected thereto, the said block connecting at one side with one terminal of the circuit and on the other side with a spring connected to the opposite terminal and having freedom to adjust itself between the two terminals.

2. The combination, in a lamp-socket, of two 35 insulated pieces H and F, the latter having means for attaching one terminal of the lamp thereto and the former carrying a spindle provided with a loose contact-block and adjusting-spring for connecting the said piece to the 40 opposite terminal of the lamp.

3. The combination, with an incandescent lamp having its two wires connected, respectively, to concentric terminals in the lamp-base, of the socket containing a switch which is constructed of two pieces attached to an insulating-disk, one of said pieces being adapted to connect with one of said terminals, while the other piece has a spindle and a switch-block adapted to connect with the opposite lamp-terminal and provided with a spring for adjusting it between the parts which it connects.

Signed at Lynn, county of Essex and State of Massachusetts, this 3d day of March, A. D. 1890.

SAMUEL DEACON.
